UNITED STATES PATENT OFFICE.

JOHN J. REILLY, OF TROY, NEW YORK.

COMPOUND UNIVERSAL CHUCK.

1,369,707.

Specification of Letters Patent. Patented Feb. 22, 1921.

Application filed March 22, 1920. Serial No. 367,302.

To all whom it may concern:

Be it known that I, JOHN J. REILLY, a citizen of the United States of America, residing at Troy, in the county of Rensselaer and State of New York, have invented certain new and useful Improvements in Compound Universal Chucks, of which the following is a specification.

This invention relates to a chuck designed particularly for use by die makers, in the use of which practically any and all characters of work may be properly held, either on a bench or in a machine, and the chuck as a whole readily and conveniently adjusted to any angle convenient for the operator in this class of work.

The improved chuck comprises a base in which the holder proper is mounted for a substantially universal movement with relation thereto, means being provided whereby such holder may be secured at any desired adjustment relative to the base. The free end of the holder is adapted for the convenient connection thereto of the immediate work support, being adapted in this particular for work supports of different character.

The invention in the preferred form of details, is shown in the accompanying drawings, in which:—

30 Figure 1 is a perspective view of the improved chuck.

Fig. 2 is a vertical longitudinal central section of the same.

Fig. 3 is a perspective view of the work holding clamp used with the chuck.

Fig. 4 is a vertical section showing the mounting of the work holding clamp shown in Fig. 3.

The improved chuck comprises a base 1, 40 preferably formed with a central threaded aperture 2, and having means whereby such base may be secured to a bench or other support when desired. The base is formed with a substantially semi-spherical socket 3, and the outer surface of the base about the upper edge of said socket is exteriorly threaded as at 4.

The holder 5 comprises a cylindrical body of appropriate length, terminating at the 50 lower end in a spherical head 6 adapted to fit more or less snugly into the socket 3. A clamping ring 7 is adapted to fit over the head 6 and bear upon the same above the socket, said clamping ring having threaded connection 8 with a threaded section 4 of the base. By this construction it is appar-

ent that the work holder is capable of substantially any annular adjustment with relation to the base, and when so adjusted may be fixed in such position through the clamping ring 7. The ring 7, while ordinarily capable of being set by the hand, is preferably provided with wrench openings 9 whereby an unusually tight set may be secured if desired, and to assist in preventing any possibility of movement of the holder when once fixed, both socket 3 and the clamping ring 7 may be formed with recesses to receive a fiber or other friction strip 10.

The holder 5 is formed with a longitudinal bore 11 extending through the same, enlarged at the upper end at 12 to receive split jaws 13, set into the enlargement. The outer surface of the holder at the upper end 75 is threaded at 14 to receive a set nut 15, the wall of the central opening of which is inclined at 16, to coöperate with inclined edges 17 of the split jaws 13. Obviously the clamping of said jaws 13 on the work may 80 be readily obtained by the proper action of the set nut 15.

For work of a different character, particularly where the work is to be turned from time to time, there is provided an additional 85 work clamp comprising jaws 18 adapted to be set through clamp screws 19, and supported on or as a part of a sleeve like member 20. The sleeve 20 is adapted to fit over the upper end of a holder 5, and is provided 90 with a spring pressed locking pin 21 adapted to engage a recess 22 in the holder 5. A set screw 23 located in the sleeve 20 diametrically opposite the pin 21, will also seat in the recess 22, which is of course an annular channel and thus the work clamp may be turned to any position, and temporarily held in that position by the obvious use of the set screw 23.

In the use of the chuck the base may be 100 fastened to the bench and if the operator is cutting stencils or seals the jaws 13 may be used to hold the work. In cutting a die the work clamp 18 may be used so that the die may be turned to any position. Of course 105 in either of these operations any desired annular position of the holder 5 relative to the base may be secured as previously explained.

Work holders or ordinary lathe chucks can be screwed on to the threaded end 14 of 110 the holder 5, and in cutting cams on a lathe or milling machine the base may be fastened

to the face plate or spindle of dividing head, and the body 5 adjusted to any angle.

What I claim is:

A work-holding body supported at one end for universal movement, said body being formed remote from its universal mounting with an annular channel, a work-holding member comprising a sleeve to rotatably fit over the body and cover said channel, a

spring-pressed pin carried by the sleeve to 10 normally seat in said channel, a set screw carried by the sleeve to be moved into said channel to hold the member fixed with relation to the body, and a fixed jaw and a relatively adjustable jaw carried by and arranged beyond the sleeve.

In testimony whereof I affix my signature.

JOHN J. REILLY.
